UNITED STATES PATENT OFFICE.

LOUIS A. ROBBINS, OF CANTON, OHIO.

COMBINED BOTTLE-CAP AND STRAINER.

1,198,959.

Specification of Letters Patent. Patented Sept. 19, 1916.

Application filed March 27, 1915. Serial No. 17,459.

To all whom it may concern:

Be it known that I, LOUIS A. ROBBINS, a citizen of the United States, residing at Canton, in the county of Stark and State of Ohio, have invented certain new and useful Improvements in Combined Bottle-Caps and Strainers; and I do hereby declare the following to be a full, clear, and exact description of the invention, such as will enable others skilled in the art to which it appertains to make and use the same.

This invention has for its primary object to provide a combined bottle cap and strainer especially designed for use in connection with milk bottles, whereby the contents of the bottle may be dispensed and strained without removing the cap bodily from the bottle.

Another object is the provision of a combined bottle cap and strainer including a strainer element secured against accidental removal from the bottle neck and constituting an anchor for the cap.

With these and other objects in view, the invention consists in the novel construction, arrangement and formation of parts as will be hereinafter specifically described, claimed and illustrated in the accompanying drawing, in which:

Figure 1 represents a fragmental longitudinal sectional view through a milk bottle of the usual construction, illustrating the invention applied to use. Fig. 2 represents a top plan view of the combined strainer and cap removed. Fig. 3 represents a bottom plan view of the bottle cap and strainer removed, and Fig. 4 represents a transverse sectional view on the line 4-4 of Fig. 2.

Referring to the drawing in detail, where in similar reference numerals designate corresponding parts throughout the several views, the numeral 5 indicates generally the bottle closure or cap adapted to frictionally engage within the circular groove or recess A formed in the open end of the neck of a bottle B.

A crease 8 is formed diametrically of the cap dividing the latter into a relatively stationary part or section 6 and a movable part or section 7 adapted to be folded back upon the section 6 to permit of the dispensation of the contents of the bottle. A tongue 9 is preferably cut out from the movable sec-

tion 7, whereby the latter may be conveniently opened.

55

A strainer element 10 is permanently secured to the relatively stationary part or section 6 of the cap by a suitable type of fastener 11 and is shaped conformably with the cap 5 and adapted to frictionally lock 60 within the annular groove or recess A in the bottle neck. The strainer element is preferably formed of a non-corrosive wire screen of adequate mesh.

In use, the bottle cap 5 and strainer element 10 are inserted in the recess or groove A in the usual manner to completely close the bottle B, and when it is desired to dispense the contents the relatively movable part or section thereof is moved, by means 70 of the tongue 9 to the position illustrated in Fig. 1. The strainer elements 10 being of the same diameter as the cap 5 is frictionally retained within the usual recess or groove A in the bottle neck B and thus insures against the accidental displacement of the bottle cap when the relatively movable part or section 7 is moved outwardly or opened in order to facilitate dispensation of the contents of the bottle. As the milk 80 or other liquid contents of the bottle is poured through the neck thereof it is clearly evident that the strainer element 10 will effectively strain the milk.

85

What I claim is:

1. In combination, a bottle cap including relatively movable and stationary sections, and a strainer element shaped conformably with said cap and secured to the relatively stationary section and constituting anchoring means for securing the latter in the neck 90 of a bottle.

2. In combination, a bottle cap adapted for insertion in the neck of a bottle and including a foldable section, and a strainer element shaped conformably with and secured to said cap and constituting anchoring means for the latter.

3. In combination, a bottle cap adapted for insertion in the neck of a bottle and including relatively stationary and foldable sections, and a strainer element secured to the relatively stationary section shaped conformably with said bottle cap and constituting anchoring means therefor.

100

4. In combination, a bottle cap including

105

relatively stationary and foldable sections, a tongue cut out from the foldable section, and a strainer element secured to the relatively stationary section and shaped conformably with said cap, of approximately the same diameter as the latter and constituting an anchoring means therefor.

In testimony whereof I affix my signature in presence of two witnesses.

LOUIS A. ROBBINS.
